UNITED STATES PATENT OFFICE.

JOHN JOHNSON, OF MANISTEE, MICHIGAN.

DESIGN FOR A CREASE-RETAINER FOR HATS.

SPECIFICATION forming part of Design No. 33,533, dated November 6, 1900.

Application filed May 23, 1900. Serial No. 17,766. Term of patent 7 years.

To all whom it may concern:

- Be it known that I, JOHN JOHNSON, a citizen of the United States of America, residing in Manistee, in the county of Manistee and State of Michigan, have invented and produced a new and original Design for a Crease-Retainer for Hats, of which the following is a specification, reference being had to the accompanying drawings, forming a part thereof.
- 10 Figure 1 is a side view in elevation of my new design. Fig. 2 is a sectional view taken transversely and vertically through the middle of Fig. 1.
- As shown in the drawings, the leading or 15 material feature of my design consists of a single sheet of elastic material so bent and formed as to provide a hollow tubular back A, with an opening or slit B extending lon-

gitudinally thereof, from the edges of which are produced slightly diverging vertical wings or flaps C, having curved edges, the curves beginning closely adjacent to the end edges of the slit in the tube and rising toward the middle, as shown in the drawings.

Having described my invention, what I claim as new, and desire to secure by Letters Patent, is—

The design for a crease-retainer for hats, as herein shown and described.

In testimony whereof I have signed my name to this specification in the presence of two subscribing witnesses.

JOHN JOHNSON.

Witnesses:

JOSEPH SAILE,
J. S. MODISON.
